[57]**CLAIM**

The ornamental design for a combined pallete-type holder and paper therefor for creating color art work, as shown and described.

DESCRIPTION

FIG. 1 is a front elevational view of the combined pallete-type holder and paper therefor for creating color art work showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof with the broken lines shown for illustrative purposes only and forming no part of the claimed design.

FIG. 1

FIG. 2

FIG. 3

FIG. 4

FIG. 5

FIG. 6

FIG. 7
